UNITED STATES PATENT OFFICE.

GEORGE LOOS, OF GRAFTON, NORTH DAKOTA.

BOX-LID HOLDER.

No. 806,548.

Specification of Letters Patent.

Patented Dec. 5, 1905.

Application filed May 18, 1905. Serial No. 260,974.

To all whom it may concern:

Be it known that I, GEORGE Loos, a citizen of the United States, and a resident of Grafton, in the county of Walsh and State of North Dakota, have invented a new and Improved Box-Lid Holder, of which the following is a full, clear, and exact description.

This invention relates to a device for holding a box-lid in an open position.

10 The invention is especially applicable to cigar-boxes.

The object of the invention is to produce a device of this class which is of very simple construction and easily applied, operating to 15 hold the lid in any position desired.

The invention consists in the construction and combination of parts to be more fully described hereinafter and definitely set forth in the claims.

20 Reference is to be had to the accompanying drawings, forming a part of this specification, in which similar characters of reference indicate corresponding parts in both views.

Figure 1 is a perspective view showing the device applied to a cigar-box, and Fig. 2 is a side elevation of the device represented as removed from the box.

Referring more particularly to the parts, 1 represents the body of a cigar-box, which is 25 provided at its rear upper edge 2 with the usual lid 3, which is adapted to fold down, so as to close the box in the usual manner. The box-lid holder 4 is applied to the box-lid, as indicated in Fig. 1, in a manner which will be 30 stated more fully hereinafter. In its construction the holder 4 comprises a main bar 5, preferably formed of stout wire, as indicated, the extremity of this bar being offset, as at 6, in an inclined direction and provided with a 35 laterally-projecting extension or foot 7. Ad-

jacent to the main bar 5 a second bar 8 is provided, which is rigidly attached to the main bar by a metal sleeve 9, located near the offset 40 6, as indicated. The bodies of these bars 45 5 and 8 diverge at their extremities 10, which lie remote from the sleeve 9, and at their points they are formed with oppositely-disposed nibs or teeth 11, which are adapted to grasp an object therebetween, as will be 50 readily understood. It should be noted that the bar 8 would preferably be of stout wire like the bar 5, and this wire would be resili- 55 ent and formed so that the extremities 10 would tend to hold themselves slightly apart.

The butt 12 of the bar 8 extends beyond the sleeve 9 in the direction of the foot 7 and

terminates a short distance from the foot, whereby an opening or jaw 13 is formed, into which the edge 14 of the box-lid may be thrust, as indicated in Fig. 1. This extremity of the device constitutes a stirrup, which holds the box-lid.

Upon the bars 5 and 8 an eye or ring 15 is mounted to slide. When the ring occupies a position near the sleeve 9, such as that indicated in Fig. 2, the extremities 10 of the bars may be spread apart, so as to allow the edge 16 of the box end to be passed into the space between the nibs 11. When the holder has been applied in the manner suggested, the 70 ring 15 would then be forced in the direction of the extremities 10, operating to draw these parts toward each other and forcing the nibs 11 into the end of the box. The point at which the nibs 11 are made to engage the 75 box end may be selected, so as to give the box-lid 3 any desired angular position. When the edge 14 of the lid is received in the space 80 13, the extremity of the butt 12 lies adjacent to the forward side of the lid, as shown, and the foot or extension 7 extends itself longitudinally of the lid, projecting under the edge and constituting a substantial support for the lid, as will be readily understood. The 85 opening or space between the butt 12 and the foot 7 is preferably slightly greater than the thickness of the lid of the cigar-box.

The device is preferably applied so that it is disposed substantially at right angles to the lid, the edge of the lid being received at 90 the foot 7, as suggested. Then the device is rotated down at its outer extremity, so as to pinch the lid between the butt 12 and the foot, and the other end of the device is then attached to the end of the cigar-box, as 95 shown.

The device described is evidently of very simple construction and may be economically manufactured. It is also easily applied to boxes of various thicknesses by reason of the construction employed for grasping the box end. It is also evident that the device may be applied to either end of the box with equal facility.

Having thus described my invention, I 105 claim as new and desire to secure by Letters Patent—

1. A holder for the lid of a box comprising an elongated member having a laterally-disposed extension adapted to rest against the 110 rear face of the open lid, said member comprising a pair of adjacent bars diverging at

the extremities thereof remote from said extension, said extremities presenting a space therebetween adapted to receive the edge of the box end, and a sliding ring mounted on 5 said bars.

2. A holder for a box-lid comprising a main bar having a laterally-disposed extension at one extremity thereof constituting a foot adapted to be applied to the rear face of 10 an open box-lid, a second bar rigidly attached to said first bar and having a butt projecting to a point near said extension, the extremi-

ties of said bars remote from said extension diverging to receive the edge of the box end therebetween and presenting nibs adapted to 15 engage the box end, and a sliding ring on said bars controlling the extremities thereof.

In testimony whereof I have signed my name to this specification in the presence of two subscribing witnesses.

GEORGE LOOS.
